UNITED STATES PATENT OFFICE.

ROBERT P. MEES, OF ST. LOUIS, MISSOURI.

SEWING-MACHINE ATTACHMENT.

No. 874,098.

Specification of Letters Patent.

Patented Dec. 17, 1907.

Application filed June 15, 1907. Serial No. 379,274.

To all whom it may concern:

Be it known that I, ROBERT P. MEES, citizen of the United States, residing at St. Louis, State of Missouri, have invented certain new and useful Improvements in Sewing-Machine Attachments, of which the following is a full, clear, and exact description, reference being had to the accompanying drawings, forming a part hereof.

10 My invention has relation to improvements in sewing machine attachments; and it consists in the novel construction and arrangement of parts more fully set forth in the specification and pointed out in the claims.

15 In the drawings, Figure 1 is a front perspective view of the lower end of a sewing machine arm showing my invention applied thereto; Fig. 2 is an elevation from one side of the presser-foot showing my invention applied thereto, a portion of the clamping plate being broken; Fig. 3 is an elevation of the opposite side of Fig. 2; Fig. 4 is a horizontal section on line 4—4 of Fig. 2; and Fig. 5 is a bottom plan of Figs. 2 and 3.

20 25 The object of my invention is to provide the presser-foot of any conventional type of chain-stitch machine with a blade the purpose of which is to trim the material at a predetermined distance from the line of stitching, so that the edges of the sewed pieces of the fabric or goods will present an even and smooth finish along the seam defined by the stitch-line. In detail the invention may be described as follows:

30 35 Referring to the drawings, A, represents the lower end of a sewing machine arm, P, the presser-foot bar, and 1, the presser-foot, the open toe variety being preferably here shown.

40 N, represents the awl-bar, and n, the awl. T, represents the throat plate, being provided with a slit s for the awl, the slit in the present instance being provided with a lateral enlarged portion s' as shown (Fig. 1) for the reception of the blade 2. The blade is provided with a terminal head 2' which is set into a rearwardly inclined recess or depression formed on the outer face of the inner toe of the presser-foot, the base of the recess being disposed parallel to the general length of the toe, or in other words, to the line of stitching.

45 50 55 The outer face of the head 2' is flush with the corresponding face of the inner toe, the head being clamped in position by a clamping plate 3 which presses against the head,

the plate itself being secured to the presser-foot by screws 4. 4. Since the opposite faces of the head 2' are parallel, and since the inner face of the head is flush or in the same plane with the inner face of the blade 2, it follows that said blade-face will be parallel to the toes of the presser-foot or to the general line of stitching; but since the blade-face referred to makes an angle with the opposite or outer face of the blade, said outer face will be inclined to the toes or to the general travel of the goods in the formation of the stitches. It is apparent that a shearing effect will be exerted on the goods as it is fed beneath the presser-foot, the complement of the shearing blade edge being furnished by the longitudinal edge of the recess s' of the slit s of the throat-plate T. The front end of the clamping plate 3 terminates a little short of the adjacent end of the toe to which it is secured, forming a shoulder or offset 5, the operator using the outer edge x of the toe projecting beyond said offset as a guide in directing the goods during the sewing operation. So that with the point x as a guide or index, the goods may always be sewed and trimmed at a uniform distance from the edges of the pieces which are united, or they may be severed along any line marked thereon, the line being passed under the point x as the goods is advancing over the throat plate. I do not of course wish to be understood that the blade or trimmer here shown is applicable to only one form of machine, but it may be attached to any presser-foot in the class of sewing machines above referred to; and the principle thereof is broad enough to include all lock-stitch sewing machines whose character will permit them to avail themselves of the trimmer qualified to meet special emergencies. In Fig. 1 the goods would be fed to the left, between the presser-foot and throat-plate, the blade severing or trimming the material conjointly with the sewing operation. The blade being secured to the presser-foot, of course has no special movement imparted thereto, the goods being severed as the same is fed against the edge of the blade by the feed of the machine.

Having described my invention what I claim is:

1. In combination with an open toe presser-foot, a rearwardly inclined depression or socket formed on the outer face of the inner toe, a blade received by said socket, and a clamping plate for securing the blade in po-

sition, the front end of the plate being located a suitable distance from the front end of the toe and forming an offset with the side of the toe to which said plate is secured, the edge of 5 the toe projecting beyond said offset serving as a guide for the fabric or material operated on, substantially as set forth.

2. In combination with a presser-foot toe, a rearwardly inclined blade depending from 10 and secured to the toe, and having one of its faces disposed diagonally to the line of feed of the material operated on, substantially as set forth.

3. In combination with a presser-foot toe, 15 a blade depending from and secured to, and inclining rearwardly from said toe, the outer face of the blade being parallel to the line of feed of the material operated on, and the inner face being diagonally disposed to such

feed line, whereby a shearing effect is produced, substantially as set forth. 20

4. In combination with an open toe presser-foot having a rearwardly inclined socket formed on the outer face of the inner toe, a blade having a terminal head received 25 by said socket, the inner face of the blade being disposed in the plane of the base of the socket, and the opposite face being disposed diagonally to said plane whereby a shearing effect is produced, and means for securing 30 the blade in position to the toe, substantially as set forth.

In testimony whereof I affix my signature, in presence of two witnesses.

ROBERT P. MEES.
